UNITED STATES PATENT OFFICE.

PERRY L. CROSSMAN, OF JOPLIN, MISSOURI.

APPARATUS FOR REPAIRING DRILLS.

SPECIFICATION forming part of Letters Patent No. 657,519, dated September 11, 1900.

Application filed February 24, 1900. Serial No. 6,374. (No model.)

To all whom it may concern:

Be it known that I, PERRY L. CROSSMAN, a citizen of the United States, residing at Joplin, in the county of Jasper and State of Missouri, have invented a new and useful Steam-Hammer, of which the following is a specification.

This invention relates to steam-hammers in general and more particularly to a hammer adapted for use in repairing the bits of drills used in the drilling of Artesian and oil wells, one object of the invention being to provide a construction which will be simple and cheap of manufacture and efficient in its operation, further objects being evident from the following specification.

In the drawings forming a portion of this specification, and in which like numerals of reference indicate similar parts in the several views, Figure 1 is a front elevation of a hammer constructed in accordance with the present invention. Fig. 2 is a side elevation of Fig. 1. Fig. 3 is a side elevation of a swaging-hammer used for forming the blade of the bit. Fig. 4 is a perspective view of the frame of the bit-jack.

Referring now to the drawings, the hammer of the present invention is mounted slidably in a frame comprising a base 5, to which are attached parallel and vertical uprights 6 and 7, which are mutually connected at their upper ends by means of a cross-piece 8, upon which is mounted a steam-cylinder 9. The upper end of this cylinder is open, and a slight distance below its open upper end are formed perforations 10.

In the cylinder 9 is disposed a piston, the rod 12 of which extends through the cross-piece 8 downwardly and between the uprights 6 and 7. As the piston 11 is reciprocated in the cylinder the rod 12 is correspondingly moved. A cross-head 13 is mounted upon the uprights 6 and 7 through the medium of ears 14 upon the cross-head and through 45 which the uprights are passed, this cross-head being attached to the piston-rod for movement therewith. The lower portion of the cross-head is tapered, as shown, and in this tapered portion is formed a recess or seat, 50 which is adapted to receive, removably, a

hammer-head 15, held in place by means of a set-screw 16 or in any other suitable manner.

In order to reciprocate the piston 11 to correspondingly move the cross-head, the lower end of the cylinder 9 is closed, and communicating with this cylinder, above its closed lower end, is a combined feed and outlet pipe 17, having a three-way valve 18 upon its outer end. One of the branches of the valve connects with a steam-exhaust pipe 19, and the third arm connects with a steam-feed pipe 20, which leads from a suitable source of steam-supply. An operating-rod for the valve 18 is shown at 21 and extends downwardly and into position to be readily grasped by the operator of the hammer. With this construction it will be seen that by operating the valve-rod 21 in one direction steam will be admitted to the cylinder 9 and the piston 11 will be forced upwardly to raise the cross-head. When the piston has reached a point above the perforations 10, the steam under pressure will escape from such openings and upward movement of the piston will be discontinued. If the valve-operating rod be 65 then moved in an opposite direction, the steam-exhaust will be opened and the steam in the cylinder will run out to permit the hammer to drop and strike a blow. The steam may be admitted, cut off, and permitted to flow out at will and in this manner the stroke of the hammer may be regulated to a nicety.

In order that a bit may be held in operative relation to the hammer and may be moved readily into and out of operative position at will, a jack is provided, which consists of a U-shaped frame 25, the extremities of the arms of which are connected to a shaft 26, which is rotatably mounted in ears 27 upon 85 the base 5 and between the uprights 6 and 7. The shaft has a lever attached thereto for rocking the shaft. The upper ends of the arms of the U-shaped frame are continued beyond the web 28 of the frame, and these extending portions are bent in the same direction to lie at right angles to the arms to receive a drill upon the web and between the arms. In the central portion of the shaft 26 is secured a block 29, in the central portion 90 95 100

of which is an opening to receive the extremity of the butt of the bit, which butt is tapered in the usual manner for engagement with a recess in the drill-shaft end. A stop-bar 30 is secured to the uprights 6 and 7 and transversely thereof, this cross-bar having an outwardly-curved portion which receives the bit in its inwardly-curved opposite face when the jack is rocked to cause the bit to stand erect. 10 When the bit is in a vertical position against the stop-bar, the web 28 lies against the opposite side of the bit and the extremities of the arms of the U-shaped frame lie on opposite sides thereof, and thus when the lever is 15 operated to move the jack, with the bit, into a reclining position the web will lie under and will support the bit.

In connection with the steam-hammer there is employed a swaging-hammer, (shown in Fig. 3 of the drawings,) and which hammer has a V-shaped groove in its head which is to be fitted over the upper end of the drill-bit. The steam-hammer is then operated to strike the swaging-hammer and drive it down upon 25 the bit with the well-known result.

Adjacent the base 5 is located an anvil 35 in such position that when the jack is operated to move the bit from under the steam-hammer it will move it onto the anvil for further operation.

As illustrated in Fig. 1 of the drawings, the cross-head 13 has a central transverse recess 35 which communicates with a perforation in the upper end of the cross-head and through 35 which perforation is passed the piston-rod 12. The lower end of the piston-rod within the recess 36 has an enlarged head, and between this head and the lower end of the recess is disposed a helical spring 38. This spring absorbs 40 the jar of the piston-rod when the head and rod are dropped and also relieves the rod of the jar when the upward movement of the cross-head is suddenly arrested.

In practice various modifications of the specific structure may be made and any suitable proportions and materials may be used without departing from the spirit of the invention.

What is claimed is—

1. A steam swaging-machine comprising 50 uprights, a cylinder carried by the uprights at the upper ends thereof, a cross-head slidably engaged with the uprights and having a spring-receiving recess and a communicating guideway, a piston in the cylinder and having 55 a rod passed through the guideway and into the recess, a spring in the recess, a head upon the rod engaging the spring, a base for the uprights, ears upon the base, a drill-holding frame pivotally mounted in the ears, a stop-bar upon the uprights in the path of movement of the drill-frame to retain said frame in operative position, and steam supply and exhaust connections with the cylinder, the cross-head having a hammer connected 60 therewith for engagement with a drill in the frame.

2. A steam swaging-machine comprising 70 uprights, a cross-head slidably engaged with the uprights, a steam-cylinder, a piston for the cylinder having a rod slidably engaged with the cross-head, a cushion between the end of the rod and the cross-head, a base for the uprights, ears upon the base, a rock-shaft 75 pivotally mounted in the ears, a drill-holder mounted upon the shaft and comprising a U-shaped bar attached at its ends to the shaft and having its end adjacent the web bent laterally and provided with a cross-bar connecting the arms of the U-shaped bar at 80 their bends to form a rectangular inclosure, a seat upon the shaft for the butt of the drill, means for rocking the shaft, and a stop-bar upon the uprights for contact by a drill in the frame to stop the drill in operative relation to the cross-head, said cross-head having 85 a hammer for engagement with the drill in the frame.

In testimony that I claim the foregoing as my own I have hereto affixed my signature in 90 the presence of two witnesses.

PERRY L. CROSSMAN.
